ABSTRACT: An apparatus for the precise measurement of very low dielectric losses of a dielectric specimen at high frequencies having a high frequency oscillator, a series tuning circuit electromagnetically coupled to the coil in a tank circuit of the high frequency oscillator and having two series-connected variable air capacitors, two tuning circuits electrostatically coupled to the series tuning circuit, and a detecting circuit having an indicating meter and inductively coupled to the parallel tuning circuits. A dielectric specimen is connected to one of the parallel tuning circuits and the zero method is utilized to measure the loss resistance of the specimen.

**DIELECTRIC LOSS MEASURING APPARATUS
EMPLOYING PLURAL TUNED CIRCUITS**

This invention relates to electrical measuring apparatus and more particularly to an apparatus for the precise measurement of electrical losses of dielectric materials.

Precise measurement of very low resistances, very high resistances and very low dielectric losses of various dielectric materials at high frequencies is increasingly required with the advance in dielectric materials for use in electrical engineering.

It is a primary object of the present invention to provide a novel and improved apparatus which satisfies the above demand.

The above and other objects, features and advantages of the present invention will be apparent from the following description when read in conjunction with the accompanying drawings, in which:

FIG. 1 is a circuit diagram of the electrical measuring apparatus of the present invention which is adapted to measure a very low dielectric loss at high frequencies by means of an electrostatic coupling system;

FIG. 2 is a circuit diagram showing details of part of the circuit diagram shown in FIG. 1;

FIGS. 3a, 3b and 3c are vector diagrams of voltages appearing in the detecting circuit;

FIG. 4a is a circuit diagram of another embodiment of the present invention which is adapted to measure a very low dielectric loss at high frequencies by means of an inductive coupling system; and

FIGS. 4b and 4c are equivalent circuit diagrams of the loss measuring section in the embodiment shown in FIG. 4a.

Referring to FIG. 1, a high frequency oscillator OSC is stabilized in its high frequency output and is associated with a tank circuit including a capacitance C_s and an inductance L_0 . A coil having an inductance L_1 is inductively coupled to the inductance L_0 with a coefficient of magnetic induction M_0 . The inductance L_1 and capacitances C_1 and C_1' form a series tuning circuit so as to measure an equivalent parallel resistance R_x of a specimen from a minute change ΔC_1 in C_1 or a minute change $\Delta C_1'$ in C_1' . The inductance L_0 has a resistance r_0 and the relation therebetween can be expressed as $\omega L_0/r_0 = Q_1$. Suppose now that $C_1 = C_1'$, then the circuit comprising L_1 , C_1 and C_1' is tuned when the relation

$$\omega^2 L_1 C_1 = 2 \quad (1)$$

holds, and the voltage appearing across C_1 becomes maximum. Variable air capacitors having the capacitances C_1 and C_1' have their rotor sides grounded in common and are electrostatically coupled to parallel tuning circuits I and II at their high voltage terminals through very small capacitances C_0 and C_0' of equal value, respectively. Coils having inductances L_2 and L_2' in the tuning circuits I and II are electromagnetically coupled to coils having inductances l_2 and l_2' in a detecting circuit with coefficients of mutual induction M_2 and M_2' of equal value, respectively.

These two tuning circuits I and II are identical in their construction and circuit constants. Thus, $L_2 = L_2'$, $R_2 = R_2'$ and $C_2 = C_2'$. When the series tuning circuit is tuned under the condition of $C_1 = C_1'$, terminal voltages e_1 and e_1' are of the same magnitude or $e_1 = e_1'$. Because of the fact that $C_0 = C_0'$, maximum voltages appear across the two tuning circuits I and II when the following conditions are satisfied:

$$\omega^2 L_2 (C_2 + C_0) = 1, \quad \omega^2 L_2' (C_2' + C_0') = 1 \quad (2)$$

The magnitudes of the maximum voltages are given by

$$e_2 = j\omega C_0 R_2 e_1, \quad e_2' = j\omega C_0' R_2' e_1' \quad (3)$$

In this case, $e_2 = e_2'$. Therefore, voltages e_x and e_x' induced across the inductances l_2 and l_2' are of the same

magnitude or $e_x = e_x'$, and the deflection of an indicating meter I_g is zero.

In the detecting circuit, a combination of a capacitance C_{02} , an inductance L and a capacitance C is provided in order to amplify a minute difference Δe_x between e_x and e_x' , the minute difference being then amplified by an amplifier A for deflecting the indicating meter I_g accordingly. In the state in which the circuits are in complete equilibrium and $I_g = 0$, the inputs e_x and e_x' to the detecting circuit have a vector relationship as shown in FIG. 3a. Then when a switch S is closed to connect a dielectric specimen (having a capacitance C_x and equivalent parallel resistance R_x) to the circuit I, e_x will now be changed into e_x' , in FIG. 3b due to the presence of C_x and R_x , and an output Δe_{x1} appears across a terminal T_1 and the ground E to cause a deflection of the indicating meter I_g . Then, the value of C_2 may be reduced to minimize the deflection of the meter I_g . In this case, e_x will have a vector as shown in FIG. 3c and the value of C_x can be obtained from the value of C_2 . The deflection of the indicating meter I_g in such a case is caused by Δe_{x2} which is dependent upon the resistance loss R_x of the specimen.

Referring next to FIG. 2, a method of seeking R_x from C_1 will be described. In the equivalent circuit of the high-frequency oscillator, the high-frequency source generating a high-frequency voltage e_s comprises a vacuum tube circuit having an internal resistance r_p . The relation between the internal resistance r_p and an equivalent parallel resistance R_0 of the tank circuit including L_0 and C_s is $R_0 \gg r_p$. Now, the voltage e_2 appearing across the tuning circuit I under the conditions of

$$\omega^2 L_1 C_1 = 2 \quad (4)$$

$$\omega^2 L_2 (C_2 + C_0) = 1 \quad (5)$$

and

$$C_1 = C_1'$$

will be sought in FIG. 2. Under the conditions that the circuits I and II are coupled to the series tuning circuit including L_1 , C_1 and C_1' through C_0 and C_0' , and under the condition that the equation (5) is satisfied, series resistances r_1 and r_1' in the series tuning circuit can be given by the following equations:

$$r_1 = \frac{C_0^2}{C_1^2} R_2$$

$$r_1' = \frac{C_0'^2}{C_1'^2} R_2'$$

hence,

$$r_1 + r_1' = \frac{C_0^2}{C_1^2} R_2 + \frac{C_0'^2}{C_1'^2} R_2' \quad (6)$$

Therefore, a resistance r_0 in series with L_0 is given by

$$r_0 = \frac{\omega^2 M_0^2}{r_0 + \frac{C_0^2}{C_1^2} R_2 + \frac{C_0'^2}{C_1'^2} R_2'} \quad (7)$$

From the relation

$$R_p = \frac{\omega^2 L_0^2}{r_0},$$

R_p can be given by

$$R_p = \frac{L_0^2}{M_0^2} \left(r_0 + \frac{C_0^2}{C_1^2} R_2 + \frac{C_0'^2}{C_1'^2} R_2' \right) \quad (8)$$

Thus,

$$e_0 = e_s x \frac{1}{1 + r_p/R_p} = e_s x \frac{\frac{L_0^2}{M_0^2} \left(r_0 + \frac{C_0^2}{C_1^2} R_2 + \frac{C_0'^2}{C_1'^2} R_2' \right)}{\frac{L_0^2}{M_0^2} \left(r_0 + \frac{C_0^2}{C_1^2} R_2 + \frac{C_0'^2}{C_1'^2} R_2' \right) + M_0^2 r_p} \quad (9)$$

$$I_0 = \frac{e_0}{\omega L_0}$$

(provided that $\omega L_0 \gg r_0$)

$$e = \omega M_0 I_0$$

$$I_1 = \frac{e}{r_0 + \frac{C_0^2}{C_1^2} R_2 + \frac{C_0^2}{C_1^2} R_{2'}}$$

$$e_1 = \frac{I_1}{\omega C_1}$$

(provided that $\omega C_1 r_1 \ll 1$)

and from $e_2 = \omega C_0 R_2 e_1$, e_2 is given by

$$e_2 = \frac{C_0}{C_1} x \frac{M_0 L_0 R_2 e_1}{L_0^2 \left(r_0 + \frac{C_0^2}{C_1^2} R_2 + \frac{C_0^2}{C_1^2} R_{2'} \right) + M_0^2 r_p} \quad (10)$$

Similarly, e_2' is given by

$$e_2' = \frac{C_0}{C_1'} x \frac{M_0 L_0 R_2' e_1}{L_0^2 \left(r_0 + \frac{C_0^2}{C_1^2} R_2 + \frac{C_0^2}{C_1^2} R_{2'} \right) + M_0^2 r_p} \quad (11)$$

The outputs or sensitivity losses due to a minute change of R_2 are given by

$$\Delta e_2 = \frac{C_0}{C_1} \frac{L_0^2 \left(r_0 + \frac{C_0^2}{C_1^2} R_{2'} \right) + M_0^2 r_p}{x M_0 L_0 e_1 R_2 \left\{ L_0^2 \left(r_0 + \frac{C_0^2}{C_1^2} R_2 + \frac{C_0^2}{C_1^2} R_{2'} \right) + M_0^2 r_p \right\}^2} x \frac{\Delta R_2}{R_2}$$

$$\Delta e_2' = -\frac{C_0}{C_1'} \frac{L_0^2 \frac{C_0^2}{C_1^2} R_2}{x M_0 L_0 e_1 R_2 x \left\{ L_0^2 \left(r_0 + \frac{C_0^2}{C_1^2} R_2 + \frac{C_0^2}{C_1^2} R_{2'} \right) + M_0^2 r_p \right\}^2} x \frac{\Delta R_2}{R_2}$$

Suppose that Δe is the difference between the voltages across the circuits I and II, then $\Delta e = \Delta e_2 - e_2'$.

Because of the fact that $C_0 = C_0'$, $C_1 = C_1'$ and $R_2 = R_2'$, Δe_2 is given by

$$\Delta e_2 = \frac{C_0}{C_1} \times \frac{M_0 L_0 R_2 e_1}{L_0^2 \left(r_0 + \frac{2C_0^2}{C_1^2} R_2 \right) + M_0^2 r_p} \times \frac{\Delta R_2}{R_2} \quad (12)$$

Voltages e_2 and e_2' appearing as a result of minute change ΔR_2 in R_2 or $R_2 \rightarrow R_2 + \Delta R_2$ will now be sought from the Equations (10) and (11) as follows:

$$e_2 = \frac{C_0}{C_1} \times \frac{M_0 L_0 (R + \Delta R_2) e_1}{L_0^2 \left\{ r_0 + \frac{C_0^2}{C_1^2} (R_2 + \Delta R_2) + \frac{C_0^2}{C_1^2} R_{2'} \right\} + M_0^2 r_p} \quad (10')$$

$$e_2' = \frac{C_0}{C_1'} \times \frac{M_0 L_0 R_2' e_1}{L_0^2 \left\{ r_0 + \frac{C_0^2}{C_1^2} (R_2 + \Delta R_2) + \frac{C_0^2}{C_1^2} R_{2'} \right\} + M_0^2 r_p} \quad (11')$$

The actual output is the difference between e_2 and e_2' in the equations (10') and (11') and acts to deflect the indicating meter. Suppose that C_1 is increased by a minute amount ΔC_1 so that the deflection becomes zero again. The voltages e_2 and e_2' when C_1 is increased to $C_1 + \Delta C_1$ are obtained from the equations (10') and (11'), and the difference therebetween is assumed to be zero or $e_2 - e_2' = 0$. Then, the denominators of the equations (10') and (11') are entirely identical with each other and are given by

$$L_0^2 \left\{ r_0 + \frac{C_0^2}{(C_1 + \Delta C_1)^2} (R_2 + \Delta R_2) + \frac{C_0^2}{C_1^2} R_{2'} \right\} + M_0^2 r_p$$

which may be expressed herein as A.

Thus,

$$\frac{C_0}{C_1 + \Delta C_1} \times \frac{M_0 L_0 R_2 e_1}{A} + \frac{C_0}{C_1 + \Delta C_1} \times \frac{M_0 L_0 R_2 e_1}{A} \times \frac{\Delta R_2}{R_2} - \frac{C_0}{C_1} \times \frac{M_0 L_0 R_2 e_1}{A} = 0$$

$$\frac{C_0}{C_1} \left(1 - \frac{\Delta C_1}{C_1} \right) \times \frac{M_0 L_0 R_2 e_1}{A} + \frac{C_0}{C_1} \left(1 - \frac{\Delta C_1}{C_1} \right) \times \frac{M_0 L_0 R_2 e_1}{A} \times \frac{\Delta R_2}{R_2} - \frac{C_0}{C_1} \times \frac{M_0 L_0 R_2 e_1}{A} \times \frac{\Delta R_2}{R_2} = 0$$

Since $C_0 = C_0'$, $C_1 = C_1'$ and $R_2 = R_2'$, the above equation can be expressed as

$$-\frac{C_0}{C_1} \times \frac{M_0 L_0 R_2 e_1}{A} \times \frac{\Delta C_1}{C_1} + \frac{C_0}{C_1} \times \frac{M_0 L_0 R_2 e_1}{A} \times \frac{\Delta R_2}{R_2} - \frac{C_0}{C_1} \times \frac{M_0 L_0 R_2 e_1}{A} \times \frac{\Delta C_1}{C_1} = 0$$

The above equation can be simplified as

$$\frac{\Delta C_1}{C_1} = \frac{\Delta R_2}{R_2} \quad (13)$$

because the third member of the equation is negligible compared with the first and second members. On the other hand, the relation

$$\frac{\Delta R_2}{R_2} = \frac{R_x}{R_x} \quad (25)$$

holds when $R_x \gg R_2$, and finally the following equation is obtained:

$$\frac{\Delta C_1}{C_1} = \frac{R_x}{R_x} \quad (30)$$

Since C_1 and R_x in the equation (14) are known values, R_x can be obtained from the value of a minute change ΔC_1 in C_1 when the output due to the presence of R_x is made zero by varying the value of C_1 .

In another embodiment shown in FIG. 4a, the apparatus comprises a power supply regulating section and a measuring section which are electromagnetically coupled to each other. The power supply regulating section includes variable air capacitors having capacitances C_1 and C_1' . Coils having inductances L_1 and L_1' are connected in parallel with the respective capacitors. The coils have respective resistances r_1 and r_1' . The magnitudes of the inductances L_1 and L_1' are selected so as to satisfy the conditions $\omega^2 L_1 C_1 > 1$ and $\omega^2 L_1' C_1' > 1$, respectively. Suppose that $C_1 = C_0$, $C_1' = C_0'$ and $C_0 = C_0'$ when the circuit including $L_{10} C_1$ and C_1' is tuned with a power source frequency f in the state in which L_1 and L_1' are not connected. In this case, voltages appearing across C_1 and C_1' are maximum under the condition

$$\omega^2 L_{10} \frac{C_0}{2} = 1.$$

Then when the inductances L_1 and L_1' are connected, the circuits are tuned under the conditions

$$C_1 = C_0 + \frac{1}{\omega^2 L_1}, \quad C_1' = C_0' + \frac{1}{\omega^2 L_1'} \quad (15)$$

and voltages e_1 and e_1' become maximum. Under the above condition, capacitances C_2 and C_2' in the measuring section are regulated to attain the tuning of tuning circuits in the measuring section. Thus, voltages e_2 and e_2' , hence voltages e_x and e_x' appearing in a detecting circuit take their maximum values. The deflection of an output indicating meter I_o is zero when $e_x = e_x'$.

The impedance Z between terminals T_1 and T_2 in the power supply regulating section is given by

$$Z = \frac{\omega L_1}{(\omega^2 L_1 C_1 - 1)^2} \sqrt{\frac{r_{t1}^2}{\omega^2 L_1^2} + (\omega^2 L_1 C_1 - 1)^2} \quad (16)$$

wherein

$$r_{t1} = \frac{\omega^2 M_1^2}{\frac{r_2}{(\omega^2 L_1 C_1 - 1)^2}}$$

Neglecting the first member under the root symbol since it is negligible compared with the second member, Z can be expressed as

$$Z = \frac{\omega L_1}{\omega^2 L_1 C_1 - 1} \quad (17)$$

From the Equation (17), the following equation can be obtained:

$$\frac{\Delta Z}{Z} = \frac{\omega^2 L_1 C_1}{\omega^2 L_1 C_1 + C_1} \Delta C_1$$

By inserting the above relation into the Equation (15), we obtain the following equation

$$\frac{\Delta Z}{Z} = \frac{\Delta C_1}{C_0} \quad (18)$$

Thus, a minute change Δe_1 in e_1 across the terminals T_1 and T_2 due to ΔC_1 is given by

$$\frac{\Delta e_1}{e_1} = \frac{\Delta Z_1}{Z_1} = \frac{\Delta C_1}{C_0} \quad (19)$$

On the other hand, the output voltages e_2 and e_2' from the measuring section when both the power supply regulating section and the measuring section in Fig. 4a are in their tuned state are given by the following equations:

$$e_2 = \frac{\omega M_2}{\omega^2 L_1 C_0} \times \frac{\omega L_2}{r_2} \times A \quad (20)$$

$$e_2' = \frac{\omega M_1'}{\omega^2 L_2' C_0'} \times \frac{\omega L_2'}{r_2'} \times A \quad (21)$$

wherein

$$A = \frac{M_0 L_0 e_s (\omega^2 L_1 C_1 - 1)^2 (\omega^2 L_1 C_1' - 1)^2}{L_0^2 [r_0 (\omega^2 L_1 C_1 - 1)^2 (\omega^2 L_1 C_1' - 1)^2 + r_1 (\omega^2 L_1 C_1 - 1)^2 + *]} \quad (25)$$

$$* \frac{\omega^2 M_1^2}{r_2} (\omega^2 L_1 C_1 - 1)^2 + r_1 (\omega^2 L_1 C_1 - 1)^2 + *$$

$$* \frac{\omega^2 M_1'^2}{r_2'} (\omega^2 L_1 C_1 - 1)^2 + M_0^2 r_D (\omega^2 L_1 C_1 - 1)^2 (\omega^2 L_1 C_1' - 1)^2 \quad (30)$$

The voltages e_2 and e_2' in the detecting circuit are equal to each other when e_2 and e_2' are of the same magnitude, and the output indicating meter indicates zero point.

When now a switch S in FIG. 4a is closed to connect a specimen to the measuring circuit, r_2 in the measuring circuit increases very slightly by Δr_2 due to r_x of the specimen. Tuning for C_x may be attained by varying the value of C_2 to C_2' . Thus, $C_x = C_2 - C_2'$. Because of the fact that r_2 is varied to $r_2 + \Delta r_2$, an output is developed to deflect the output indicating meter. The capacitance C_0 is very slightly reduced by an amount ΔC_1 to reduce the output to zero again. Then, from the equations (20) and (21), we obtain

$$e_2 = \frac{\omega M_1}{\omega^2 L_1 (C_0 - \Delta C_1)} \times \frac{\omega L_2}{r_2 + \Delta r_2} \times A' \quad (45)$$

$$e_2' = \frac{\omega M_1'}{\omega^2 L_1' C_0'} \times \frac{\omega L_2'}{r_2'} \times A'$$

Since $e_2 = e_2'$, and since $M_1 = M_1'$, $C_0 = C_0'$, $L_1 = L_1'$, $L_2 = L_2'$ and $r_2 = r_2'$ because both the circuits are completely similar to each other, we obtain the following equation:

$$\frac{1}{C_0} \left(1 + \frac{\Delta C_1}{C_0} \right) \frac{1}{r_2} \left(1 - \frac{\Delta r_2}{r_2} \right) = \frac{1}{C_0 r_2} \quad (55)$$

hence,

$$\frac{1}{C_0 r_2} \left(\frac{\Delta C_1}{C_0} - \frac{\Delta r_2}{r_2} - \frac{\Delta C_1}{C_0} \times \frac{\Delta r_2}{r_2} \right) = 0$$

Since

$$\frac{\Delta C_1}{C_1} \leq 0.01$$

and

$$\frac{\Delta r_2}{r_2} \leq 0.01,$$

we may neglect the third member in the parentheses in the above equation and obtain the following equation:

$$\frac{\Delta C_1}{C_0} = \frac{\Delta r_2}{r_2} \quad (22)$$

Thus, Δr_2 , hence r_x can be sought from the equation (22) because C_0 , r_2 and ΔC_1 are known. It will be understood that r_x is expressed as

$$r_x = \frac{C_2^2}{C_x^2} \Delta r_2.$$

Since ΔC_1 can precisely be measured from a change in indication in the dial graduations of the standard variable air capacitor, the value of Δr_2 can accurately be measured.

Alternatively, the output due to Δr_2 may be made zero by changing C_0 to $C_0 - \Delta C_1$ and C_0' to $C_0' + \Delta C_1$. In this case, from the equations (20) and (21), we obtain

$$\frac{\omega M_1}{\omega^2 L_1 (C_0 - \Delta C_1)} \times \frac{\omega L_2}{r_2 + \Delta r_2} \times A' \\ = \frac{\omega M_1'}{\omega^2 L_1' (C_0' + \Delta C_1')} \times \frac{\omega L_2'}{r_2'} \times A,$$

hence,

$$\left(1 + \frac{\Delta C_1}{C_0} \right) \left(1 - \frac{\Delta r_2}{r_2} \right) = 1 - \frac{\Delta C_1'}{C_0}$$

and finally

$$\frac{2\Delta C_1'}{C_0} = \frac{\Delta r_2}{r_2}$$

More precisely, the relation $\Delta C_1' = \frac{1}{2} \Delta C_1$ is obtained in this case. This second method is featured by the fact that the variation in the tuned state of the series tuning circuit due to ΔC_1 is less than in the first method.

From the foregoing description, it will be understood that the present invention employs the zero method in which precisely variable air capacitors are manipulated for the precise measurement of resistance, and in the detecting section, a minute difference voltage is solely amplified for deflecting an indicating meter whereby to measure a very small loss.

What I claim is:

1. An apparatus for the precise measurement of very low dielectric losses of a dielectric specimen at high frequencies comprising:

a stabilized high frequency oscillator;

a tank circuit connected to said oscillator;

a resonant circuit electromagnetically coupled to said tank circuit, and having an inductor and two variable air capacitors of equal capacity all connected in series, said capacitors being grounded at their common connected ends;

first and second parallel tuned circuits having the same construction and circuit constants each having one end grounded and each being electrostatically coupled to said resonant circuit at the opposite ends of said grounded capacitors through very small capacitances of equal value;

a secondary detecting circuit coupled to said first and second parallel tuned circuits;

indicator means responsive to the vectorial addition of voltages of opposite phase in said detecting circuit for providing a manifestation of the resonance of said first and second tuned circuits;

and circuit means for connecting said specimen in parallel with said first parallel tuned circuit.

55 2. The apparatus according to claim 1, further comprising means for differentially varying the capacitances of resonant circuit.

3. The apparatus according to claim 1, in which said first and second parallel tuned circuits include respective variable 60 capacitors grounded at their one ends.

4. The apparatus according to claim 1, in which said variable air capacitors are grounded at their rotors.

5. An apparatus for the precise measurement of very low dielectric losses of a dielectric specimen at high frequencies comprising:

a stabilized high frequency oscillator;

a tank circuit connected to said oscillator;

a resonant circuit having an inductor coupled to the coil of said tank circuit and first and second variable capacitors all connected in series, said first and second capacitors being grounded at their one ends and being of equal capacity;

first and second coils having the same construction and circuit constants connected in parallel with said first and second capacitors, the capacitances C_1 and C_1' of said

first and second capacitors and the inductances L_1 and L_1' of said first and second coils having the relations of $\omega^2 L_1 C_1 > 1$ and $\omega^2 L_1' C_1' > 1$, where ω represents angle frequency, with said first and second variable capacitors being adjusted to maintain said series tuning circuit at resonance;

5

first and second tuned circuits each having the same construction and circuit constants, said first and second tuned circuits having third and fourth coils respectively, said third and fourth coils being electromagnetically coupled to said first and second coils with the same coupling respectively;

an indicating circuit having inductors electromagnetically coupled to said third and fourth coils and an indicating meter whose deflection is set at zero under normal conditions so that the output voltages from said first and second circuits in their tuned state are equal to each other;

and circuit means having test electrodes coupled to said first tuned circuit for connecting one specimen in parallel with the former;

whereby the loss and capacitance components of the specimen under test are derivable from a minute change in at least one of the series-connected capacitors when the output of said detecting input due to the presence of the specimen is made zero.

6. The apparatus according to claim 5 which further comprises means for differentially varying the capacitances of said resonant circuit.

7. The apparatus according to claim 5 in which said first and second parallel tuning circuits includes respective variable capacitors grounded at their one ends.

8. The apparatus according to claim 5 in which said variable air capacitors are grounded at their rotors.
